DENTURE TRAY

Arthur Jutras, Saint Hyacinthe, Quebec, Canada

Application June 16, 1950, Serial No. 168,588

4 Claims. (Cl. 32—17)

1

The present invention pertains to a novel dental tray for receiving plaster or other plastic material in making impressions of the gums and palate.

The principal object of the invention is to provide a denture tray that is not entirely solid so that it will not compress or deform the palate and gums to be impressed. Another object is to provide a tray in which the flexible portion may be varied. Still another object is to provide a denture tray which is easy to use and to clean.

Finally, a further object of the invention is to provide a tray which is of simple construction and economical to manufacture.

In the accomplishment of these objects, the tray consists of a metal member in the form of an upper or lower denture, partial or complete. The lower edge of this member is curved outwardly and receives a similarly curved piece of rubber forming the bottom. The lower edge of the tray is preferably toothed or notched in order to attach more securely to the rubber piece.

The invention is fully disclosed by way of example in the following description and in the accompanying drawings in which:

Figure 1 is a perspective view of the frame of the tray;

Figure 2 is a section on the line 2—2 of Figure 1;

Figure 3 is a perspective view of the complete tray;

Figure 4 is a vertical section illustrating the use of the device;

Figure 5 is a section on the line 5—5 of Figure 1;

Figure 6 is a similar section of a tray for the lower denture;

Figure 7 is a section on the line 7—7 of Figure 3;

Figure 8 is a similar section of a tray for the lower denture;

Figure 9 is a perspective view of a modified lower denture tray;

Figure 10 is a perspective view of a modified upper denture tray;

Figure 11 is a perspective view showing a handle applied to a tray;

Figure 12 is a section on the line 12—12 of Figure 11;

Figure 13 is a perspective view showing a modified handle applied to a tray, and

Figure 14 is a section on the line 14—14 of Figure 13.

Reference to these views will now be made by use of like characters which are employed to designate corresponding parts throughout.

2

In Figures 1 and 2 is shown a metal member 1 shaped to receive an upper denture. This member is in the nature of a frame of somewhat heart-shape, laminated or molded, and having an internal rear vertical wall 2 and sloped downward and rearward at 3 at the front.

The upper edge is bent outward at 4 at the rear, and the lower edge is bent outward and upward at 5 at the front to form a U-channel. At 10 regular intervals the edge of the bend 5 is toothed at 6 for the attachment of a rubber bottom piece 7 which also has a doubled edge 8 to be received within the bend 5 or channel.

The sectional views shown in Figures 6 and 8 15 pertain to lower dentures. As this tray is not in the form of a basin but rather a channel, its contour is similar to that shown in Figure 9. Figures 6 and 8 illustrate the doubled edges 9 on both the inner and outer sides of the channel for receiving a piece of rubber 10 (Figure 8) at its doubled edges 11.

Figures 9 and 10 show a simpler method of 20 making upper and lower denture trays. The inner wall 12 of the frame 13 is vertical, and this is easier to form than the diverging wall 3 of Figure 1. The doubled or bent edge 5 remains as above described, as well as the teeth 6'. In the tray for the upper denture, shown in Figure 10, the internal wall 14 is also vertical while the edge 30 5'' and teeth 6'' remain as above described.

As shown in Figure 4, the tray receives a quantity of plaster 15, after the wall has been lined with wax or other suitable plastic material 16 for better tightness. It is understood that, in order to take a good impression of the gums 17 and palate 18, it is necessary to compress the tray. Heretofore, the metal tray of spoon form pushed the plaster against the palate, deforming it until it became flexible. 35 The impression thus made had a crown that did not conform to the shape of the palate. The resulting dentures injured the palate and never adapted themselves thereto.

In the present invention, the bottom or center of the tray being flexible because of the 40 rubber sheet 7 which permits displacement of the plaster 15, the plaster is distributed over the palate but does not exert more pressure in one area than in another. The flexibility of the 45 piece 7 permits it to receive a surplus of plaster and prevents a non-uniform pressure on the palate. The same is true of the gums since they are enclosed in the pieces 7 and 10.

The trays can also be used with the usual 50 handles or holders. In Figures 11 and 12 a flat

handle 20 is riveted to the bottom of the upper denture tray 21 at the front. In Figures 13 and 14 an angled handle 22 is riveted to the front bottom of the lower denture tray 23. The handles are used only in starting an impression, and the impression completed by use of rubber sheet, as described, attached to the lip 24 or 25.

Although specific embodiments of the invention have been illustrated and described, it will be understood that various alterations in the details of construction may be made without departing from the scope of the invention as indicated by the appended claims.

What I claim is:

1. In a denture tray, a frame adapted to receive the gum, an outwardly and upwardly curved lower edge integral on said frame, and a flexible bottom adapted for attachment to said edge.
2. In a denture tray, a frame adapted to receive the gum, an outwardly curved lower edge integral on said frame, said edge being toothed, and a flexible bottom adapted for attachment to said edge.

3. In a denture tray, a frame adapted to receive the gum, an outwardly and upwardly curved lower edge integral on said frame, said edge being toothed, and a flexible bottom adapted for attachment to said edge.

5. 4. A denture tray comprising a frame having an enclosing wall, a shorter wall surrounding the first wall and secured thereto in spaced relation, the upper edge of the second wall being toothed, and an elastic sheet shaped to span the enclosure for the first wall and attached to the second wall.

ARTHUR JUTRAS.
